UNITED STATES PATENT OFFICE.

ALBERT H. LOUCKS, OF MARION, INDIANA, ASSIGNOR TO MARION MACHINE, FOUNDRY
& SUPPLY CO., OF MARION, INDIANA, A CORPORATION.

SOOT BLOWER.

Application filed August 14, 1924. Serial No. 732,020.

This invention relates to certain improvements in soot blowers of the type having a blow tube mounted in the head plate of the steam blower, with a blow tube extension removably connected with the blow tube so that the blow tube and extension are rotatable as a unit with a series of ports in said extension inclosed by a stationary steam head which applies steam thereto, and the means shown and described for mounting and operating said extension.

The full nature of the invention will be understood from the accompanying drawings and the following description and claims.

In the drawings Fig. 1 is a vertical central section through the soot blower, intermediate portions being broken out and omitted and other parts being shown in elevation, the valve mechanism being shown in the closed position.

Fig. 2 is a similar view of the pressure supply line and valve mechanism associated therewith showing the same in the open or pressure supplying position.

Fig. 3 is an elevation of the right hand side of the lower portion of Fig. 2.

In the drawings there is shown a wall box 10 adapted to be mounted in a steam boiler in rigid position and extending towards the flues, not shown, and having an outer head plate 11 in which the soot blower is mounted. Within and longitudinally of the wall box, part of the blow tube 12 is located, it having nozzles not shown for the exit of steam and the like therefrom for directing the steam against the boiler tubes, as is well known in the art. The outer end of the tube 12 is screwed or otherwise secured to a tubular coupling 13 carrying a sleeve 14 rotatably mounted in plate 11. The outer end of the coupling 13 is screwed or otherwise secured to the blow tube extension 15 that extends to the outer end of the blow head mechanism. It is observed that the extension tube 15, coupling 13 and blow tube 12 constitute one continuous rotatable blow tube construction for the passage of steam to and through the blow tube.

The steam or similar pressure fluid enters the blow tube extension 15 through an annular series of peripherally arranged ports or openings 16 and through which steam passes from a chamber in the steam head 116

communicating with a gooseneck or offset

steam pipe fitting 17, which is supplied with steam through a pipe or riser 18, in turn supplied by the main 19. The gooseneck is held in place by a bar 20, which is secured by a bolt 21 to the plate 11, said gooseneck 17 carrying an ear 22 which connects the strap 20 to the gooseneck 17 in rigid relation.

The steam head 116 has a chamber entirely surrounding the blow tube extension 15 and the series of ports 16 therein, and to prevent any relative lateral displacement of the steam head and tube extension, there are outwardly turned shoulders 60 on the tube extension 15. To enable the steam head to be mounted on the tube, it is formed of right and left hand sections secured together by bolts 61 and abutting against the shoulders 60, as shown. Suitable packing means 62 and 63 are associated with said steam head sections and surround the tube extension 15, for rendering the chamber in the steam head 116 steam tight, and yet permit the blow tube construction to turn easily in said head. The outer end of the tube extension 15 is closed and the lower end of the steam head 116 is flanged and bolted to the flanged upper end of the steam conduit or gooseneck 17, as shown.

By the foregoing arrangement the steam head is held rigid and furnishes a firm bearing for the tube extension 15 of the blow tube construction, so that the parts of the blow tube construction will be maintained in alignment and be perfectly balanced in the steam head, and the steam will enter equally through the ports 16 as the head 116 is considerably spaced from the ports so as to provide the chamber entirely surrounding all the ports.

The head of the gooseneck 17 is recessed as at 23 to receive a ring member 24, which includes a valve seat 25. Extending axially of said valve seat is a stem 26 slidably supported in the bearing 27 which is of fluid tight construction. The stem 26 carries a valve 28 which is adapted to engage the seat 25 and close the fluid supplying passage. It will be observed from a comparison of Figs. 1 and 2 that the valve 28 is normally maintained upon its seat by the fluid pressure.

The valve actuating mechanism consists of a bracket construction including a pair of complementary pipe embracing clamps 29 suitably secured together in pipe engaging

and adjusted position by the bolts 30 and 31 and said clamp construction constitutes a lever support for there is provided in each of the projecting ends thereof a pivot 32. 5 Pivots supported thereby is a weighted lever 33 including a socket 34 and provided with a pin 35 or suitable cable support. Said lever 33 is provided with a stop 36 and a handle forming extension 37, which 10 is weighted if desired.

A cable 38 has one end passed around the support 35 and said end 39 is clamped to the body portion 38 by the clamp construction 40. Any other equivalent and adjustable 15 construction may be substituted for the foregoing cable anchorage. The other end of the cable 38 is connected to a link 41 connected to a spring 42 anchored as at 43 to the gooseneck construction. A lever 44 is pivotally supported at 45 on an ear 46 carried by the gooseneck construction. The lever 44 is pivotally connected at 47 to said link 41. The lever 44 includes an elongated slot 48 and said slot is adapted to receive a pin 49 which 20 extends transversely of the stem 26 and is secured thereto through a block 50. A nut is associated with said stem and block for adjustment purposes.

The operation of the valve mechanism is 30 as follows. A single throw of the lever 33 from the position shown in Fig. 1 to the position shown in Fig. 2 throws the connection 35 on the lever 33 past center pins 32 as indicated by the dotted lines in Fig. 2. The 35 spring 42 tends to retain the lever 33 against movement from either of its extreme positions on opposite sides of a dead center. The single throw of the lever, which is relatively quick, secures substantially instantaneous opening of the valve 28 since the link 41 moves the lever 44 that causes pin 49 carried by block 50 to move into the position shown in Fig. 2. When the valve is open, the steam pressure in the supply line 18 40 cannot close the valve or change lever 44 and cable 38 to reposition the handle or control lever 33 in other than the position shown in Fig. 2. The lever 33 is pivoted so as to oscillate vertically. When in its downward 45 position as indicated in Fig. 2, after passing the dead center, the lever holds the valve in its opened position and in such position overcomes the pull of spring 42 until it is moved back to the upper position. When the handle, however, is again actuated and moved from the position shown in Fig. 2 to the position shown in Fig. 1, the spring 42 tends to seat the valve 26 and hold the weighted lever in the elevated position. 50 This seating action is accelerated and maintained by the steam pressure supplied to line 18, thereby cutting off the steam supply to the swivel tube and blow tube construction. The pressure also helps to hold the 55 weighted lever elevated.

From the foregoing it will be readily apparent that with the exception of the adjustable, detachable clamp 29 all of the valve mechanism is assembled and associated with the gooseneck 17, and thus the installation 70 of the blow tube is a relatively simple matter, for all that is necessary is to adjustably and rigidly secure the clamp 29 at the desired position upon the riser 18 and make a final adjustment through the cable clamp 75 40. The stop 36, as is illustrated in Fig. 2, limits excessive over-center or locking movement.

In addition to the foregoing feature of the invention the following is to be observed. 80 The sleeve 14 is secured on sleeve 13 by set screw 56 and is herein shown formed integral with a sprocket wheel 150 and said sprocket wheel is adapted to be associated with a chain 51 in mesh with a pinion 52 85 carried by shaft 53, in turn rotatable by handwheel 54. The pinion and handwheel construction is adjustably but rigidly, as well as rotatably, mounted upon the pipe 18 by the bracket arrangement 55 or equivalent 90 mounting. Rotation of the handwheel 54 rotates sleeve 14 and, therefore, coupling 13 and tube 12, and extension 15. Herein the connecting portion between the sleeve 14 and the sprocket gear 150 is shown provided with an annular flange 57 that is grooved as at 58. The peripheral groove 58 is adapted to receive a tongue 59 of a bracket member 60 which is detachably but rigidly associated with a complementary bearing portion 61 by means of the bolt and nut construction 62.

The bearing portion 61 and bracket 60 are carried by the outwardly extending end 63 on the upper end of bar 20. The foregoing 105 arrangement strengthens the mounting of the sprocket wheel 150 so that the pull of the chain 51 will not tend to distort or destroy the alignment of the parts of the blow tube construction as maintained in position 110 by plate 11 and the steam head 116.

The invention claimed is:

1. A soot blower mechanism including the combination of a wall box head plate and a blow tube rotatably mounted therein adapted to be mounted in a boiler, a blow tube extension removably connected with said blow tube and extending outwardly therefrom and in alignment therewith so that the blow tube and said extension are rotatable as a unit, said extension tube being closed at its outer end and intermediate its ends having a peripheral series of ports, a rigid valve-controlled steam conduit, a steam head mounted on and carried by said steam conduit and independent of said head plate and surrounding the blow tube extension and spaced from the series of ports therein so as to furnish a steam chamber surrounding the ports, a sprocket wheel concentric of the 120

blow tube extension and rigidly secured to said extension near the head plate, downwardly extending means for operating said sprocket wheel, and means secured to said head plate for resisting the tendency to downward movement on the part of said sprocket wheel while it is being turned by said first mentioned means.

2. A soot blower mechanism substantially as set forth in claim 1, in which said means for resisting the tendency to downward

movement on the part of the sprocket wheel consists of an annular flange connected with the sprocket wheel, and means secured to and extending from the head plate upon which the underside of said flange rests and rides as the wheel is turned, substantially as set forth. 15

In witness whereof, I have hereunto affixed my signature.

ALBERT H. LOUCKS.
